(57) **CLAIM**

I claim the ornamental design for a tool container with clip, as shown.

DESCRIPTION

FIG. 1 is a front view of a tool container with clip according to my new design;
FIG. 2 is a rear view thereof;
FIG. 3 is a top view thereof;
FIG. 4 is a bottom view thereof;
FIG. 5 is a side view thereof;
FIG. 6 is a second side view thereof;
FIG. 7 is a perspective view thereof; and,
FIG. 8 is a further perspective view of a tool container with clip according to my design, illustrating the open lid and rotated clip-hanger.
